SWEEPING MECHANISM FOR BOWLING
ALLEYS

Ivol J. Snyder, Omaha, Nebr.

Application December 23, 1946, Serial No. 717,989

1 Claim. (Cl. 273—54)

1

This invention has to do with the field of recreation and refers more specifically to the so called game of "bowling," the object being as is well known, to level a number of up-standing pins through the medium of a rolling ball in a minimum number of tries.

It is of common knowledge that the usual type of bowling alley necessitates a pin setter to remove all of the knocked down pins and replace the same in an upright position where successive bowlers may again take their turn in attempts to level the same.

Many attempts in recent years have been made to provide automatic mechanism for removing the pins from the alley and returning the same to an upright position but many difficulties have arisen particularly with respect to effective mechanism for removing all the pins from the alley prior to their being elevated or otherwise returned to the alley in the upright spaced-apart position.

It is the primary object of this invention therefore, to provide a sweeping mechanism for bowling alleys having unique and automatic means for clearing all the pins still remaining on the alley itself and moving the same to a position where other mechanism may be satisfactorily used to convey the pins to a resetting position.

The most important object of this invention is to provide a sweeping mechanism for bowling alleys having a reciprocable sweep arm movable along the longitudinal uppermost surface of the alley for removing all the pins remaining on the alley whether the same still remain in the up-standing position or have been previously leveled, which mechanism has means for returning the same arm to the original starting position.

Another important object of this invention is to provide a sweeping mechanism for bowling alleys having a track disposed along a portion of at least one longitudinal edge of the alley wherein is reciprocably mounted a follower having swingably mounted thereto a sweep arm for removing the pins from the alley as the said follower reciprocates and additionally to provide means cooperable with the said track and mounted on the swingable arm for causing the latter to swing to and from a position in overlying transverse relation to the alley as the same leaves and approaches respectively one end of its path of travel.

A still further object of this invention is to provide a reciprocable and swingable sweep arm of the aforesaid character having actuating means therefor, capable of moving the arm from

2

one end of the alley to the end thereof having the pins adjacent thereto and to return the said arm to the starting position.

Another object of this invention includes the unique manner in which the swingable paddle or arm is attached to the reciprocating mechanism therefor to the end that the same is caused to swing by said mechanism when the arm is at one end of its path of travel.

10 Additional objects of this invention will be made clear or become apparent during the course of the following specification, referring to the accompanying drawings, wherein:

Fig. 1 is a fragmentary top plan view of a bowling alley having the sweeping mechanism forming a part of my present invention associated therewith.

Fig. 2 is a longitudinal cross-sectional view taken on line II—II of Fig. 1.

20 Fig. 3 is an enlarged detailed cross-sectional view taken on line III—III of Fig. 2.

Fig. 4 is a cross-sectional view taken on line IV—IV of Fig. 2.

Fig. 5 is a detailed fragmentary cross-sectional view taken on line V—V of Fig. 2 looking in the direction of the arrows.

Fig. 6 is an enlarged cross-sectional view taken on line VI—VI of Fig. 2; and

Fig. 7 is a fragmentary detailed cross-sectional view taken on line VII—VII of Fig. 2.

Reference to Fig. 1 of the drawings clearly shows a conventional bowling alley broadly designated by the numeral 10 which comprises the regulation platform or floor-like surface having a pair of gutters 12 along the marginal edges thereof and a number of pins 14 arranged in the conventional manner at one end of alley 10. It is contemplated that the mechanism about to be described be used in conjunction with a plurality of alleys 10 and therefore, the uppermost portion of Fig. 1 of the drawings indicates an adjoining alley having a side gutter 15.

As is well known, it is the object of the player to level the alley 10 of all the pins 14 in the first bowl for scoring a so-called "strike," or if this is not accomplished in one attempt, the second bowl may be attempted and if the pins 14 are all knocked over, the player has what is called a "spare." Obviously in these two attempts, all 40 of the pins 14 may well be knocked from the alley 10 into a pit 16 at one end thereof whereupon these pins may be elevated to a position for resetting by any of various types of mechanism (not shown in the drawings). It is more common, 50 however, that one or more of the pins 14 will not

fall into the pit 16 but will fall and remain on alley 10 or in one of the gutters 12 and it is to the removal of such pins into pit 16 that this invention is directed.

A medium through which this object is attained is through use of a pair of swingable paddles or arms 18 disposed along the longitudinal edges of the alley 10 for movement to and from an overlying position with respect to the uppermost face of alley 10 and thence for reciprocation toward and from the pit 16. Obviously, the same purpose may well be accomplished through the use of only one arm 18, which arm, when in operative position, extends virtually the entire width of alley 10 but it has been found to be more practical to form such mechanism in the manner disclosed to the end that a more positive and quick acting, sweeping operation is attained.

In forming the mechanism for use with a number of side-by-side alleys 10, tracks 20 and 22 extend along a portion of the longitudinal length of alley 10 and at each side thereof and these tracks each comprise a U-shaped member disposed in the manner clearly illustrated in Fig. 6. In other words, the uppermost track 20 is mounted in opposed spaced relation to the lower track 22 and held in such spaced relation by a number of "spacers" 24 mounted on the innermost face of the bottom wall of each of the tracks 20 and 22, as clearly shown in Fig. 4 of the drawings. Such construction presents two pairs of opposed edges at the free ends of the legs of the tracks 20 and 22 within which is mounted a pair of guide blocks 26, each of which is provided with a pair of slots 38 formed in the opposite edges thereof for riding in embracing relation and sliding movement along the tracks 20 and 22. Each of these guide blocks 26 has an extension 30 on one end thereof for receiving a bifurcated end 32 of the paddle 18 through which bifurcated end, a pin 34 passes for pivotally mounting the arm 18 to the guide block 26. These arms 18 are each substantially L-shaped as illustrated in Fig. 5 and one leg thereof having pin 34 therein is provided with a pair of stub pins 36 disposed on each side of one leg of either track 20 or 22. These stub pins 36 extend upwardly on one of the arms 18 and downwardly on the other arm 18 operable with the adjoining alley 10 and as the guide blocks 26 move in a direction toward the pit 16 pulling the arms 18 therewith, the stub pins 36 riding along an arcuate portion 38 of the track 20 or 22 as the case may be, will cause arm 18 to swing laterally to a position in transverse overlying relation with the upper surface of alley 10. Conversely, as block 26 returns to the end of track 20 opposite to pit 16, these pins 36 will guide and hold arms 18 in such transverse relation relative to alley 10 until the pins 36 approach the arcuate portion 38 whereupon arms 18 will swing to a position where its longitudinal axis is substantially parallel to the longitudinal axis of alley 10, all by reason of the pivotal movement of arms 18 on block 26 at pin 34.

The operating mechanism for causing the blocks 26 and the arms 18 carried thereby to reciprocate along the longitudinal axis of tracks 20 and 22 includes endless chains 40 which pass over pairs of spaced-apart sprockets 42 and 44 which sprockets are mounted within the tracks 20 and 22 in the manner detailed in Fig. 6 of the drawings.

A bearing support 45 mounted in the track 22 and fixed to the lowermost wall thereof through the medium of a pair of bolts or the like 46, ex-

tends upwardly therefrom and has a bearing 48 within which is rotatably mounted a collar 50. This collar 50 has a flange at each end thereof, one of which flanges is secured to the innermost face of either the sprocket wheel 42 or 44 forming a part of the sweeping mechanism for one of alleys 10, by welding or the like 52.

The sprocket wheel 42 or 44 for use with the adjoining alley 10 is also mounted upon this bearing support 45 through the medium of a shaft 54 fixed thereto and passing through collar 50 and through the opposite sprocket 42 or 44. The end of the shaft 54 opposite to the sprocket 42 or 44 to which it is affixed, is provided with a screw and washer assembly 56 for holding the entire assembly together. In other words, it is clear in Fig. 6 that one of the sprockets 42 and one sprocket 44 has its collar 50 rotatable in the bearing 48 and that the opposite sprocket 42 and opposite sprocket 44 has its shaft 54 rotatable within the collar 50. The endless chain 40 thus supported by the sprockets 42 and 44 and disposed in the manner illustrated in Fig. 2 has a number of laterally projecting pins 58 thereon. These pins are engaged by the sprockets of sprocket wheels 60 and 62 respectively disposed at one end of the tracks 20 and 22 and mounted upon a pair of drive shafts 64 and 66 respectively. In other words, as illustrated in Fig. 1, each of the shafts 64 and 66 has a sprocket 62 on one end thereof and a sprocket 60 on the opposite end thereof and these shafts 64 and 66 are each driven by a suitable prime mover (not shown) connected by a belt or the like to a sheave wheel 68.

Each of the guide blocks 26 is connected to its respective chain 40 through the medium of a link 70 pivotally mounted at one end thereof to chain 40 as at 72 and pivotally secured to the block 26 as at 74.

Assuming the component parts of the sweeping mechanism just described to be formed and assembled in the manner set forth, the operation thereof is as follows:

The prime mover for rotating shafts 64 and 66 may have means conveniently located for rendering the same operable and as these shafts 64 or 66 rotate to rotate their respective sprockets 60 and 62, the chains 40 at each side of the alley 10 will be driven to pull the links 70 in a direction toward the pit 16 whereupon the blocks 26 will slide along the tracks 20 and 22. Such action causes the arms 18 to swing laterally from the position shown in Fig. 1 to a position where the same are in transverse relation to alley 10. As the blocks 26 continue to move toward the pit 16, the arms 18 will be pulled therewith until the same come into contact with any pins 36 remaining on alley 10 or in the gutters 12 and these pins will be pushed into the pit 16 for subsequent removal and resetting.

As the link 70 approaches the sprocket wheel 44, the connection 72 thereof to chain 40 will pass around sprocket wheel 44 and return toward the point of beginning, thus moving guide block 26 and the arm 18 carried thereby in a reverse movement toward the starting position.

As the stub pins 36 come into contact with the arcuate portion 38 of the track 20 or 22, as the case may be, the arm 18 will again swing to the normal position shown in Fig. 1. At this end of the cycle of operation, the connection 72 of the link 70 will pass around the sprocket wheel 42 preparatory to the next operation of the device. For best operation, it is advisable to dispose the

tracks 20 and 22 in a position far enough above the upper surface of alley 10 to maintain the arms 18 in an elevated position above alley 10 as the same reciprocate thereabove as is clear in Fig. 2. Such spacing of arms 18 from alley 10 must be small enough to assure removal of all the pins 14 both from alley 10 and the gutters 12.

While only one modification of the sweeping mechanism for bowling alleys has been shown and described, it is understood that many changes and modifications may be made without departing from the spirit of the invention and the scope of the appended claim.

Having thus described the invention, what is claimed as new and desired to be secured by Letters Patent is:

Sweeping mechanism for a bowling alley comprising at least one elongated track parallel with and adjacent to one longitudinal edge of said alley; a follower carried by the track for reciprocation longitudinally therealong; means operably connected with the follower for reciprocating the same; an elongated arm on the follower, normally extending outwardly from the track in perpendicular relationship thereto and overlying at least a portion of said alley; and guides

on the arm engageable with the track for holding the arm perpendicular to the track as the follower and the arm are reciprocated, said arm being swingable on a vertical axis with respect to the follower, said track having an arcuate end for receiving said guides as the arm is moved to one end of its path of travel whereby to swing the arm on said axis to a position out of overlying relationship to the alley and parallel with said edge thereof.
